ATTORNEY

UNITED STATES PATENT OFFICE

HUBERT INDEN, OF DUSSELDORF, GERMANY

MAKING DOUBLE-CONE SOCKET JOINTS

Application filed September 7, 1928, Serial No. 304,481, and in Germany May 4, 1928.

Object of the invention is a device which renders it possible to turn or thread double-couplings or socket-joints, as used, e. g. in conjunction with deep-boring tools (augers, 5 wimbles), upon an ordinary lathe, without the necessity of resetting the socket. The device also makes possible the adjustment of the chasers to vary the thread-diameter.

The accompanying drawing shows the new 10 device in

Figs. 1 and 2 attached to an ordinary lathe, whilst

Fig. 3 represents an enlarged longitudinal section of the new device and a part of the 15 lathe;

Figs. 4-6 illustrate details of the device.

Upon an ordinary lathe 6 the shaft 3 is placed between the centre 1 in the head-stock 4 and the centre line 2 on the tail-stock 5. 20 Upon the shaft 3 two conical cam sleeves 7 and 8 are adjustably disposed. The sleeves 7 and 8 have their conical portions provided with an annular series of slots 9, 10 in such a manner, that fingers or tongues 11, 12, 25 arranged in each series in alternation with the slots, are formed. The fingers and slots are of like width with the result, that the slotted and fingered portions of the sleeves 7, 8 may be telescopically engaged. The 30 outer cylindrical end of the conical sleeve 7 and its tongues 11 serve for supporting a set of chasers or cutters 13, whereas the cylindrical end of the sleeve 8 and the tongues 12 serve for supporting a set of 35 chasers or cutters 14. The sets of chasers are radially adjustable in accurately milled slots 15 in a cylindrical holding sleeve 16 made to fit the cylindrical parts of the sleeves 7, 8. The chasers are prevented from dropping out by means of helical draw-springs 17 40 engaging notches therein, and whereby the chasers 13, 14 are held pressed against the cylindrical end portions or the tongues of the sleeves 7, 8. The sleeve 16 is prevented from turning independently of the sleeves 7, 8 by means of the two screws 18, 19 which engage slots 20, 21 in the sleeve 16 and permit adjustment of the sleeves 7, 8 in an axial direction 45 so that couplings of different lengths and diameters may be operated upon thereby. In-

stead of the screw-cutting devices 7, 8, 13, 14 shown in the drawings, a turning or boring device similar to the screw-cutting devices except for the form of the cutters, may be placed in position between the centres 1, 2 55 after removing the screw-cutting devices. The coupling 22 to be provided with screw-thread is clamped in a lathe-chuck connected with the head stock 4 by means of the arm 22. The tightening of the gripping jaws is effected, e. g. by turning to the right a screw-cap 25, to cause the conical wedge jaws 24 to engage the conical surface of a chuck.

The modus operandi is now as follows:

The coupling 22 to be worked is clamped 60 in the lathe-chuck and first turned, which is effected by means of a turning tool of the character described. The manner of working of the turning device is practically identical with the modus operandi described 70 when cutting the thread, for which reason only the latter operation will be specifically described. For the purpose of ensuring that the coupling 22, when placed in position, will always occupy the same position in an axial 75 direction, the coupling 22 is pushed right up against the interchangeable or adjustable stop or abutment 27. The screw-cutting device is now placed in the position represented in Fig. 3. The chasers 13 are thereby 80 brought to bear against the highest portions of the cam surfaces of the conical tongues 11, whilst the chasers 14 are brought to bear against the lowest portions of the cam surfaces of the conical tongues 12. The right 85 end of the cylindrical socket 16 which has now been pushed to the right as far as it will go, carries a bearing bracket 28, firmly connected with it, and which is attached to the upper part 29 of the slide-carriage 30. Upon setting the lathe into action, the head stock revolves and with it the coupling to be provided with screw-threads. Meanwhile the slide-carriage 30 is drawn to the left in the usual manner by means of the threaded drive 90 spindle 31 of the lathe 6, the threads of which correspond in pitch to the pitch of the screw threads to be formed on the coupling. Chasers 13 will thereby be pushed inwards and the chasers 14 outwards. In this 100

way the double-cone threads will be cut, accurately in accordance with the shape of the cones 11, 12. Once the device has been properly and correctly adjusted, which can very easily be attained by means of the screws 18, 19, by axially displacing the two cones, the couplings turned out will be of absolute uniformity, without requiring special skill on the part of the operator. After the screw-cutting of the coupling has been completed, the coupling is removed and another applied in its place.

The turning or drilling of the double-cone socket is effected with another drilling-tool, which is of the same design, as the one previously described, with the only difference, that in place of thread cutters turning cutters of suitable type will be used. In contra-distinction to the modus operandi previously described, the sleeve 16 need not be displaced from the right to the left by the guide-spindle 31, but the displacement may be effected in the direction from left to right by the guide-spindle of the lathe which in this case will act as feed shaft. After the turning operation has been completed, the operator, by employing this modus operandi, is able to detach the turning device and to place the screw-cutting device in position, without the necessity of loosening the lathe-chuck. It is therefore possible, without re-setting the coupling, to provide the turned coupling with screw-threads by the use of the previously described screw-cutting device. In this way it is possible to turn out nicely finished couplings more economically than before by means of unskilled labor.

What I claim is:

1. A device for use in turning or threading double conical couplings upon an ordinary lathe, comprising a shaft adapted to be held between the head and the tail stocks of the lathe, two reversely arranged cam members of conical shape situated upon said shaft, cutting tools radially adjustable by said cam members, means for moving the cutting tools in an axial direction along said cam members, and a hollow support having means of attachment to the lathe and adapted to support the coupling so as to be acted upon by the cutting tools.

2. A device for use in turning or threading double conical couplings upon an ordinary lathe, comprising a shaft adapted to be held between the head stock and the tail stock of the lathe, a hollow chuck having means for attaching it to the lathe coaxially with the shaft for holding the coupling in position, two reversely arranged cam sleeves externally of conical shape situated upon said shaft and adjustable with relation to each other along the latter and having telescoping tongues, cutting tools radially adjustable by said tongues, and means for feeding the cutting tools in an axial direction and holding

the cam sleeves from independent rotation on the shaft, whereby said cutting tools successively operate upon the cone portions of the coupling.

3. A device for use in turning or threading double conical couplings upon an ordinary lathe, comprising a shaft adapted to be held between the head stock and the tail stock of the lathe, a sleeve attached to the face-plate of the lathe coaxially with said shaft, a chuck carried by said sleeve for holding the coupling, two relatively adjustable reversely arranged cam members externally of conical shape the taper of which corresponds to that of the completed socket and having telescopically engaging tongues, cutting tools resting on and radially adjusted by said tongues, an annular spring pressing said cutters against the tongues, and a sleeve carrying the cutters and attached to and movable with the slide carriage of the lathe.

4. A device for use in turning or threading double conical couplings upon an ordinary lathe, comprising a shaft adapted to be held between the head stock and the tail stock of the lathe, a sleeve attached to a fixed part of the lathe coaxially with the shaft, a chuck carried thereby for holding the coupling, two relatively adjustable reversely arranged cam sleeves externally of conical shape mounted on said shaft, having telescoping tapered tongues the taper of which corresponds to that of the tapered portions of the coupling, resiliently pressed cutting tools resting on and radially adjustable by said tongues, a sleeve within which the tools are arranged and extending through the coupling, said sleeve being connected with the slide carriage of the lathe for back and forth feed motion so that the coupling may be turned in one direction of feed motion and provided with screw-threads on its reverse direction of feed motion on a change of tools but without re-setting the coupling.

In testimony whereof I affix my signature.
HUBERT INDEN.
